UNITED STATES PATENT OFFICE

141,701

DESIGN FOR A TOY BOAT

August Rietzke, Gordons Corners, N. J.

Application March 1, 1945, Serial No. 118,197

Term of patent 14 years

(Cl. D34—15)

To all whom it may concern:

Be it known that I, August Rietzke, a citizen of the United States, residing at Gordons Corners, in the county of Monmouth and State of New Jersey, have invented a new, original, and ornamental Design for a Toy Boat, of which the following is a specification, reference being had to the accompanying drawing, forming part thereof.

Fig. 1 is a perspective view of a toy boat showing my new design;

Fig. 2 is a front elevational view; and

Fig. 3 is a rear elevational view thereof.

I claim:

The ornamental design for a toy boat, substantially as shown.

AUGUST RIETZKE.
